ABSTRACT

An explosive device is formed by an elongated, tapered tube closed at the smaller diameter end. A carrying handle is formed on the closed end. The interior of the tube is filled with an explosive material, such as a mixture of ammonium nitrate and a liquid hydrocarbon. A cap is sealed across the larger diameter end of the tube.

EXPLOSIVE DEVICE AND CONTAINER

In recent years extensive use has been made of explosives formed by mixing ammonium nitrate with liquid hydrocarbons, such as fuel oil. This material is considerably less expensive than traditional explosives: dynamite, nitroglycerine and TNT. It is also much safer to handle and store. Since the ammonium nitrate is usually employed in the form of small prills, a need exists for suitable containers to package the material for storage, transportation and positioning the charge in the region that the charge is to be detonated. For applications such as a seismic exploration, elongated tubes of relatively small diameter have been used to package the explosive and lower the package into a shot hole. For blasting operations which require relatively large charges, various types of bags and other flexible packages have been employed. In blasting operations which are conducted in moist areas, it is necessary to supply a container which is waterproof.

The present invention is directed toward providing an improved container and explosive device which is particularly suitable for use with ammonium nitrate containing explosives. The container is formed from an elongated tapered tube which is provided with a carrying handle at the smaller diameter end. The tube can advantageously be formed of a thermoplastic material, such as polyethylene. The tapered configuration permits a plurality of tubes to be nested for transportation and storage. After the tube is filled with explosive material, a cap is sealed to the larger diameter end, such as by fusion of the thermoplastic materials employed to form the container and cap. This provides a watertight explosive package.

In the accompanying drawing,

FIG. 1 is a view, shown partially in section, of the explosive device of this invention.

FIG. 2 is a view taken along line 2—2 in FIG. 1.

FIG. 3 illustrates the handle formed on the end of the tube.

Referring now to the drawing in detail and to FIG. 1 in particular, there is shown an elongated tube 10 which is closed at a first end 11 and which has an integral carrying handle 12 formed thereon. Tube 10 is of generally circular cross-section along its length and is provided with a slight taper so that a plurality of empty tubes can be nested. A plurality of longitudinally extending ribs 13 are formed on the outer surface of the tube. These ribs serve to strengthen the tube and to facilitate removal of individual tubes from a nested stack. Tube 10 initially is open at the second end 14. However, end 14 is provided with an outwardly flared shoulder 15 which is adapted to receive a cup-shaped cap 16.

In order to convert the container into an explosive device, the interior of tube 10 is filled with an explosive 17, such as a mixture of ammonium nitrate and liquid hydrocarbon. A conventional fuel oil can be employed to advantage for this purpose. Cap 16 is then inserted into the second end of the tube and is sealed to the tube to form a liquid-tight container. This sealing can be accomplished by applying a heating element to the ends of tube 10 and cap 16 to provide a fused area 18. Tube 10 is advantageously formed of a thermoplastic material such as polyethylene, and can be formed by conventional blow molding procedures. Cap 16 is formed of a suitable thermoplastic material, such as polyethylene, which can be sealed

to tube 10 by the application of heat. Handle 12 permits the filled container to be carried to the region of usage.

In one specific embodiment of this invention, tube 10 was formed of polyethylene and had an overall length of approximately 30 inches. The outer diameter of end 14 was approximately 8½ inches, and the outer diameter of end 11 was approximately 7½ inches. Twelve ribs 13 were formed on the outer surface of the tube. Each rib was approximately one-eighth inch wide and extended above the surface of the tube approximately one-sixteenth inch. A container of this size is capable of holding approximately 50 pounds of ammonium nitrate-fuel oil explosive mixture. Any suitable detonator can be secured to the outer surface of the container, either on the side or on the end.

While this invention has been described in conjunction with a presently preferred embodiment, it should be evident that it is not limited thereto.

What is claimed is:

1. An explosive device comprising:

a hollow tube which is closed at one end and open at the other end and which is tapered along its length with said one end being of smaller cross-sectional area than said other end so that the tube can be nested with another tube of like configuration prior to being formed into the explosive device, said tube being provided with means to facilitate separation from another tube with which said tube is nested, said means comprising a plurality of ribs extending longitudinally along substantially the entire length of the tube in spaced relationship with one another, said ribs being positioned on the external surface of the tube and extending outwardly therefrom; a carrying handle formed at said one end of said tube; a mass of explosive material disposed in said tube; and a cap sealed across said second end of said tube to seal the explosive material within the tube.

2. The explosive device of claim 1 wherein said handle is integrally formed in said first end of said tube.

3. The explosive device of claim 1 wherein said tube and cap are formed of thermoplastic material and the cap is heat sealed to said second end of the tube to form a watertight container.

4. The explosive device of claim 3 wherein said explosive material is a mixture of ammonium nitrate and a liquid hydrocarbon.

5. A container adapted to be used in forming an explosive device, said container comprising a hollow tube which is closed at one end and open at the other end, said tube having a handle formed at said one end, said tube being tapered along its length with said one end being of smaller cross-sectional area than said other end so that the tube can be nested with another tube of like configuration prior to being formed into an explosive device and, said tube being provided with means to facilitate separation from another tube with which said tube is nested, said means comprising a plurality of ribs extending longitudinally along substantially the entire length of the tube in spaced relationship with one another, said ribs being positioned on the external surface of the tube and extending outwardly therefrom.
